UNITED STATES PATENT OFFICE.

SOLOMON D. GILKERSON, OF MONTREAL, QUEBEC, CANADA.

GARMENT-FORM.

1,196,943.

Specification of Letters Patent. Patented Sept. 5, 1916.

Application filed August 5, 1915. Serial No. 43,885.

To all whom it may concern:

Be it known that I, SOLOMON D. GILKERSON, a citizen of the Dominion of Canada, and resident of the city of Montreal, in the Province of Quebec and Dominion of Canada, have invented certain new and useful Improvements in Garment-Forms, of which the following is a full, clear, and exact description.

10 This invention relates to improvements in garment forms, and the object is to provide a simple and inexpensive form which may be manufactured at small cost, and which will hold a garment in its natural shape during shipment or storage.

15 A further object is to provide a garment form which may be packed flat when not in use, and adjusted for use to have surface curvature closely resembling the curvature 20 of the human body.

25 The device consists essentially of a sheet of material slit from the upper corners in approximately a diagonal direction to form the upper portion thereof into central and side divisions, provided with interlocking means. The central division carries at its upper edge a neck tab having laterally extending arms, which may be folded over the central division to form with the neck tab 30 a collar support.

35 In the drawings which illustrate the invention:—Figure 1 is a plan view of the form in flat condition. Fig. 2 is a plan view of the form in folded condition.

40 Referring more particularly to the drawings, 11 designates a sheet of material of the contour shown in Fig. 1 having slits 12 formed therein and extending from the upper corners downwardly toward the vertical axis of the sheet, so as to divide the upper portion of the sheet into a central division 13 and a pair of side divisions 14. The central division is provided along the upper edge with slots 15 for the reception of the 45 upper ends of the side divisions 14, which are provided with hooks 16 for the purpose of retaining the side divisions in the slots. The central division is provided in suitable positions with U-shaped cuts forming 50 tongues 17 integral with the sheet, and arranged to engage adjacent edges of the side divisions whereby the edges are gripped between the tongues of the central division. The neck tab 18 is foldable with respect to 55 the central division at a crease line 19, and

is again foldable intermediate its ends at a crease line 20 parallel with the crease 19. An arm 21 extends from each side of the neck tab extending a suitable distance laterally. These arms may be foldable with respect to the neck tab at crease lines 22. Slots 23 are provided in the central division in position to receive the ends of the arms 21. The extremity of the neck tab is provided with an aperture 24 by which the device may be suspended. A transverse slot 25 is provided in the lower portion of the sheet in order that another garment may be hung therethrough.

60 In assembling the device to operative form, the free ends of the side divisions 14 are pressed toward one another until they overlap the central division, and the ends thereof become introduceable through the slots 15, where they will be held by the hooks 16. The adjacent edges of these side divisions are inserted under the tongues 17 simultaneously with or subsequently to the insertion of their ends in the slots 15, so that the side divisions are held down on the 65 central division by being gripped between the tongues and the central division, and are thereby spaced a predetermined distance apart. The neck tab is bent upwardly at the crease 19, and if desired, downwardly at the crease 20. The arms 21 are then brought 70 forwardly over the central division, and a quarter turn imparted to them, so that the ends lie flat on the central division and may be inserted through the slots 23, where they 75 will be held. The overlapping of the central and side divisions produces the surface curvature in the sheet, as will be readily understood, while the tongues 17 hold the side divisions against excessive overlapping intermediate their ends, when pressure is applied to the convex surface of the form. The positioning of the arms 21 forms 80 a support of natural shape for the collar of a garment, so that the same does not become creased by being folded flat in a box or from the weight of the garment when 85 the form is suspended. When adjusted to operative form, the outer edges of the side divisions, which it will be noted curve outwardly at the upper edges, will form laterally projecting portions arranged to engage in the arm holes of a garment. The 90 formation of the center and side divisions in the upper part of the garment enables an 95 100 105 110

extremely natural curvature to be produced when the divisions are adjusted to overlapping position, and it has been found that the effect produced with divisions thus formed is much better than when the divisions are formed in the lower part of the sheet.

Having thus described my invention, what I claim is:—

- 10 1. In a device of the character described, a sheet of material divided from the top into central and side divisions, means on said side divisions for engaging the central division, and integral means on the central division for engaging the side divisions intermediate of their length.
- 20 2. In a device of the character described, a sheet of material divided from the top into central and side divisions, means on said side divisions for engaging the central divisions, and integral independent means

on the central division for gripping the side divisions above and below.

3. In a device of the character described, a sheet of material widest in the upper portion and separated into central and side divisions by slits extending obliquely from the upper corners, slots in the upper corners of the central division positioned to receive the free extremities of the side divisions, hooks on the side divisions arranged to retain the ends thereof in the slots, and tongues formed integral with the central division positioned for engagement with adjacent edges of the side divisions.

In witness whereof, I have hereunto set my hand, in presence of two witnesses.

SOLOMON D. GILKERSON.
